DELEADING OF GASOLINE

Morris S. Kharasch, Chicago, Ill., assignor to the
United States of America as represented by the
Secretary of the Army

No Drawing. Application May 4, 1948,
Serial No. 25,091

19 Claims. (Cl. 196—44)

1

The invention described herein, if patented, may be manufactured and used by or for the Government for governmental purposes, without the payment to me of any royalty thereon.

The invention described herein relates to a process for removing tetraethyl lead from leaded gasoline, and more particularly to a process in which the leaded gasoline is treated with a perhydrohalide of a tertiary amine to precipitate the tetraethyl lead, and the precipitate then settled out by treatment with an absorbent substance such as charcoal having a developed internal surface.

Because of the fact that most of the internal combustion engines in use today are of the high-compression type and operate more efficiently on fuel of high-octane rating, the base stock of most fuels is treated with tetraethyl lead compounds to increase the octane rating of the fuel. However, certain apparatus of the type used by the armed forces in the field and by farmers and others, such as low-compression engines, gasoline lanterns and gasoline stoves, does not operate satisfactorily with leaded gasoline because lead deposits are formed on such vital parts as valves and burner tips. In many cases, unleaded fuel is not readily available to those having need of it, so that a method of quickly and inexpensively deleading leaded gasoline is desirable.

Heretofore, several methods have been devised for deleading leaded gasoline, but it has been found that in actual practice these methods do not produce results as satisfactory as desired because they require too much time, they increase the gum content of the gasoline to an undesirable extent, they remove the dye from the gasoline but very little of the tetraethyl lead, the volume of treating agent required relative to the volume of gasoline deleaded is so large that the methods are impracticable or the gasoline is left with acid constituents or other undesirable constituents.

In one of these methods a relatively small quantity of stannic chloride is mixed with the leaded gasoline. This reacts with the tetraethyl lead to form diethyllead dichloride and diethyltin dichloride which being insoluble in gasoline are precipitated. Any stannic chloride in excess of that required to precipitate out the lead is removed from the gasoline by adding water in order to prevent polymerization of unsaturated hydrocarbons in the gasoline which would increase the gum content to an undesirable extent. Although this process accomplishes the removal of tetraethyl lead from gasoline in a fairly satis-

2

factory manner it requires a good deal of time to complete a deleading operation and results in the waste of a rather large quantity of the gasoline being treated. In addition undesirable acid constituents remain in the deleaded gasoline after treatment.

In my improved process for deleading gasoline I initially add to the leaded gasoline a relatively small quantity of a perhydrohalide of a tertiary amine; the perhydrohalide yields free hydrohalides which in turn react with the tetraethyl lead to form a triethyl lead halide. The precipitate is then absorbed from the gasoline solution by charcoal. The reaction may be represented by the formulae:

In order to provide intimate contact of the gasoline and the reactant, it is necessary to stir or shake them vigorously, say, for about ten minutes. Inasmuch as most charcoals do not quickly absorb the triethyl lead halide formed by the reaction of the tetraethyl lead contained in the gasoline with the perhydrohalide, about 10 hours should be allowed for the absorption step. After that time, the gasoline may be slowly decanted, or preferably passed through a filter while being drawn off, in order to remove any fine bits of charcoal and/or precipitate which may remain suspended in the solution.

Accordingly, it is an object of the invention to provide a new and improved process for removing tetraethyl lead from gasoline in which the tetraethyl lead is precipitated from leaded gasoline with a tertiary amine perhydrohalide and the precipitate settled out by adding charcoal to the mixture.

Another object of my invention is the precipitation of tetraethyl lead from gasoline by reacting the former with a hydrogen halide, which is added to the leaded gasoline in chemically bound form.

A further object of the invention is the provision of a new and improved process for deleading gasoline which is inexpensive and may be readily carried out on any desired quantity of gasoline with a minimum of equipment so that the process is adaptable for use by the armed forces in the field or by others desiring gasoline when only leaded gasoline is available.

In order to disclose the process sufficiently to permit the practice thereof, an example of a deleading operation performed on a one gallon lot of leaded gasoline will be described. To

3

one gallon of gasoline substantially free from olefinic groups containing 2.25 ml./gal. of tetraethyl lead and having a gum content of 8 mg./100 ml. are added to 10 ml. of triethylamineperhydrobromide made in accordance with the process described in Example I, and the mixture is shaken at intervals for 10 minutes. 44 g. of Norit A charcoal (a charcoal having a highly developed internal surface) are added, and the mixture is again shaken for ten minutes, and subsequently allowed to stand for about 10 hours. Finally, the charcoal which now has absorbed the precipitated organo-lead is removed by filtration, e. g., by passing the gasoline through a cloth or fine mesh screen. A residue of gasoline should be permitted to remain in the container, as it is likely to be contaminated with charcoal and precipitate remnants. The tetraethyl lead content of the treated gasoline is now only about .26 ml./gal. or slightly more than 10% of the original tetraethyl lead content, the gum content however, increases to about 24-28 mg./100 ml.

The process of the present invention thus produces favorable results with "saturated" gasolines; however, I have found that when applied to highly unsaturated gasoline (that is, gasoline having a large admixture of olefins), it reduces the tetraethyl lead content appreciably (though not as much as in the case of saturated gasoline), but has the undesirable tendency of considerably increasing the gum content of the "unsaturated" gasoline. Thus, a gasoline of highly unsaturated gasoline containing 2.25 ml./gal. tetraethyl lead, treated in accordance with the method described in the preceding paragraph, gave a product containing an .89 ml./gal. tetraethyl lead and 385 mg./100 ml. gum. Such a gasoline, while still useful for purposes such as combustion in open burner gasoline stoves, is not particularly desirable in internal combustion engines or other machines where gum deposits would be disadvantageous.

Beside Norit A charcoal, other commercial charcoals with developed internal surface such as Nuchar, a product of the West Virginia Paper and Pulp Company, may be used. The settling time of about 10 hours after addition of the charcoal is desirable, because shorter settling periods result in appreciably higher organo-lead residues in the treated gasoline, as appears from the following table:

Time of Standing with Charcoal	Lead Content (ml. tetraethyl lead/gal.)	Gum Content (mg./100 ml.)
1 hour.....	0.48	49
2 hours.....	.45	56
5 hours.....	.44	27
10 hours.....	.26	24

Among the perhydrohalides of tertiary amines, which are found to be useful in the deleading of gasoline in accordance with the above method, are the perhydrobromides of triethylamine, tripropylamine, tributylamine, and triamylamine. The corresponding perhydrochlorides react more slowly with the tetraethyl lead, and are therefore less suitable than the perhydrobromides.

The perhydrobromides and perhydrochlorides of other tertiary amines, such as those of dimethylaniline, allyldiethylamine, or n-amylene-diethylamine are not as effective as deleading agents as the perhydrohalides of trialkylamines, because they are not as stable as the latter.

4

Several specific examples for the production of tertiary amine perhydrohalides are given below:

Example 1

5 Triethylamine (111.6 g.) is placed in a 500 cc. flask equipped with an inlet tube terminating above the liquid and an exit tube guarded with calcium chloride. The flask is then cooled to -80° C. in a Dry-Ice-acetone bath. Hydrogen bromide is passed into the flask. At first, a solid mass of triethylamine hydrobromide is formed; however, as more hydrogen bromide is added, the solid dissolves. After the solid has vanished, the solution is warmed to room temperature, and the excess hydrogen bromide is allowed to escape. The hydrogen bromide absorbed by the amine amounts to 257 g., or approximately 3 moles of hydrogen bromide per mole of amine. The product triethylamine perhydrobromide

is a colorless liquid with an appreciable vapor pressure.

Example 2

25 The reaction of Example 1 is carried out with gaseous hydrogen chloride instead of hydrogen bromide. At first, a solid mass of triethylamine hydrochloride is formed, which however, dissolves as more hydrogen is added. After all 30 solids have dissolved, the solution is warmed to room temperature and the excess hydrogen chloride allowed to escape. Approximately 3 moles of hydrogen chloride are taken up by one amine mole. The triethylamine perhydrochloride

is a colorless liquid with an appreciable vapor pressure.

Example 3

40 The reaction of Example 1 is carried out with tripropylamine (melting point -93.5° C.) and hydrogen bromide as the reagents, in a Dry-Ice-acetone bath at about -80° C., and the supply of hydrogen bromide is continued until all tripropylamine monohydrobromide, which initially forms as an intermediary product is dissolved. Tripropylamine perhydrobromide

50 remains in the vessel after the excess hydrogen bromide has been permitted to escape.

The reaction may be represented by the equation

wherein R_1^1 , R_2^1 , and R_3^1 are hydrocarbon radicals,

60 X is a halogen atom, and n is 2 or 3. R_1^1 , R_2^1 and R_3^1 may be either identical (as in the case of triethylamine) or non-identical (as in the case of dimethylaniline or allyldiethylamine); however,

I have found that trimethylamine does not form 65 a perhydrohalide, and that at least one of the hydrocarbon groups attached to the central nitrogen atom must contain 2 or more carbon atoms.

An excess of the hydrohalide above the stoichiometric proportions represented by the above 70 equation should be used; the excess portion which is not taken up by the tertiary amine is evaporated and may be recovered in the final step of the process. It is desirable that it be carried out at a low temperature, e. g., at about -80°

C, such as is provided by a Dry-Ice-acetone bath. However, other low temperatures, such as temperatures of the order of -30° C. to -120° C. are also suitable; the selected temperature should be above the melting point of the tertiary amine selected as the starting material.

Other tertiary perhydrohalides may be formed in the same manner as that described in the preceding examples, by substituting liquid tertiary amines of the general formula

for those given in the preceding examples. The temperature of the cooling bath should be higher than the melting point of the amine selected as the starting material. Pyridine

does not form a perhydrohalide if treated in accordance with the method described in the specification. Tertiary amines with unsaturated organic radicals, such as allyldiethylamine, take up additional moles of hydrocarbon halide at the double bond; thus allyldiethylamine and an excess of hydrogen bromide or hydrochloride form dibromopropyl diethylamine perhydrobromide, and dichloropropyl diethylamine perhydrochloride, respectively.

Thus:

The reaction products of tertiary amines and excess hydrogen halide are themselves highly reactive because of the ease with which they give up hydrogen halide.

They are thus useful as halogenating agents, and particularly in organo-metallic reactions, such as in the deleading of gasoline.

The above described examples of a method for deleading gasoline are described for the purpose of disclosing the steps to be performed in carrying out a deleading operation in accordance with my improved method. It will be obvious that modifications may be made in the process disclosed without departing from the scope of the invention, hence I do not wish to be limited to the precise process above described but desire to include within the scope of the invention all those modifications included in the claims set forth below.

I claim:

1. The process of deleading gasoline containing tetraethyl lead which comprises adding a perhydrohalide of a tertiary amine to the gasoline and then treating the mixture with charcoal to adsorb the reaction product and settle out the same.

2. The process of deleading gasoline containing tetraethyl lead which comprises adding a perhydrobromide of a tertiary amine to the gasoline and then treating the mixture with charcoal to adsorb the reaction product and settle out the same.

3. The process of deleading gasoline containing tetraethyl lead which comprises adding a perhydrochloride of a tertiary amine to the gasoline and then treating the mixture with charcoal to

adsorb the reaction product and settle out the same.

4. The process of deleading gasoline containing tetraethyl lead which comprises adding a perhydrohalide of an alkyl amine to the gasoline and then treating the mixture with charcoal to adsorb the reaction product and settle out the same.

5. The process of deleading gasoline containing tetraethyl lead which comprises adding a perhydrobromide of an alkyl amine to the gasoline and then treating the mixture with charcoal to adsorb the reaction product and settle out the same.

6. The process of deleading gasoline containing tetraethyl lead which comprises adding a perhydrochloride of an alkyl amine to the gasoline and then treating the mixture with charcoal to adsorb the reaction product and settle out the same.

7. The process of deleading gasoline containing tetraethyl lead which comprises adding a perhydrohalide of a trialkylamine, said trialkylamine having from 2 to 5 carbon atoms in a chain attached to the nitrogen atom, to the gasoline and then treating the mixture with charcoal to adsorb the reaction product and settle out the same.

8. The process of deleading gasoline containing tetraethyl lead which comprises adding a perhydrobromide of a trialkylamine, said trialkylamine having from 2 to 5 carbon atoms in a chain attached to the nitrogen atom, to the gasoline and then treating the mixture with charcoal to adsorb the reaction product and settle out the same.

9. The process of deleading gasoline containing tetraethyl lead which comprises adding a perhydrochloride of a trialkylamine, said trialkylamine having from 2 to 5 carbon atoms in a chain attached to the nitrogen atom, to the gasoline and then treating the mixture with charcoal to adsorb the reaction product and settle out the same.

10. The process of deleading gasoline containing tetraethyl lead which comprises adding a perhydrohalide of triethylamine to the gasoline and then treating the mixture with charcoal to adsorb the reaction product and settle out the same.

11. The process of deleading gasoline containing tetraethyl lead which comprises adding triethylamine perhydrobromide to the gasoline and then treating the mixture with charcoal to adsorb the reaction product and settle out the same.

12. The process of deleading gasoline containing tetraethyl lead which comprises adding triethylamine perhydrochloride to the gasoline and then treating the mixture with charcoal to adsorb the reaction product and settle out the same.

13. The process of deleading gasoline containing tetraethyl lead which comprises adding to the gasoline a perhydrohalide capable of yielding a hydrogen halide, and then treating the mixture with charcoal to adsorb the reaction product and settle out the same.

14. The process of deleading gasoline containing tetraethyl lead which comprises adding a perhydrobromide capable of yielding hydrogen bromide to the gasoline, and then treating the mixture with charcoal to adsorb the reaction product and settle out the same.

15. The process of deleading gasoline containing tetraethyl lead which comprises adding to the gasoline a perhydrochloride capable of yielding hydrogen chloride, and then treating the mixture with charcoal to adsorb the reaction product and settle out the same.

16. The process of deleading gasoline containing a tetraethyl lead which comprises adding about 10 parts by volume of triethylamine perhydrobromide per 2.25 parts by volume of tetraethyl lead contained in said gasoline, agitating said mixture, and treating the mixture with charcoal to adsorb the precipitated organo-metal compound.

17. The process of deleading gasoline containing tetraethyl lead which comprises adding about 10 parts by volume of triethylamine perhydrobromide per 2.25 parts by volume of tetraethyl lead contained in said gasoline, agitating said mixture for about 10 minutes and treating the mixture with charcoal to adsorb the precipitated organo-metal compound.

18. The process of claim 16 wherein the step

5 of treating said mixture with said charcoal has a duration of about 10 hours.

19. The process of claim 17, wherein the step of treating said mixture with said charcoal has a duration of about 10 hours.
